GASIFYING APPARATUS

Frank J. Termany, Lake Hiawatha, N. J.

Application January 27, 1955, Serial No. 484,352

6 Claims. (Cl. 48—107)

My invention relates to improvements in gasifying apparatus for converting fuel oil into fuel gas.

The primary object of my invention is to provide for quickly converting such oil into a hot dry gas from which the low grade waxes and tars have been completely removed.

Another object is to provide apparatus for the above purposes which eliminates drip traps and is proof against flare-backs causing explosion, and compact and readily portable.

Still another object is to provide apparatus for attaining the above objectives by atomization and combustion in cold humid climates and which is foolproof and inexpensive to manufacture, and adapted to generate instantaneous blue gas.

Other and subordinate objects, together with the precise nature of my improvements, will become apparent when the succeeding description and claims are read with reference to the accompanying drawings in which:

Figure 1 is a view in vertical section of my improved apparatus in the preferred embodiment thereof;

Figure 2 is a view in horizontal section taken on the line 2—2 of Figure 1;

Figure 3 is a view in horizontal section taken on the line 3—3 of Figure 1; and

Figure 4 is a fragmentary view in horizontal section taken on the line 4—4 of Figure 1.

Referring to the drawings by numerals, the apparatus of my invention comprises an upright outer cylindrical shell 1 having a bottom 3 and an annular top closure plate 5 bolted to said shell, as at 7, on a sealing gasket 9.

A second cylindrical upright shell 11 depends from the closure plate, with which it is integrally formed, into the outer shell 1 concentrically thereof with a closed bottom 13 and is smaller in diameter and shorter to space the same from the side and bottom of said outer shell 1.

A third upright shell 15 extends from the opening 17 in the cover plate 5 to the bottom 13 of the second shell 11 within the second shell 11 concentrically thereof and is formed integrally with said plate 5 and bottom 13 and spaced from the side of the second shell 11 to form therewith an annular gas discharge chamber 16 in the second shell 11.

A turret 19 surrounding the opening 17 in the closure plate 5 rises from said plate 5 and is formed of upper and lower fitting sections 21, 23 bolted together, as at 25, with a sealing gasket 27 therebetween and the lower section 23 bolted to the closure plate 5, as at 29, on a sealing gasket 31.

A right angled oil supply pipe 33 from a suitable source of hydrocarbon fuel oil under pressure extends into one side of the upper section 21 through a gland nut 35 and depends into the lower fitting 23 with a downwardly discharging atomizer bulb 35 thereon in the lower fitting 23 and inside the upper end of an upright fourth cylindrical shell 37 suspended by an upper end 39 from said bulb and spaced concentrically from said lower fitting 23 and the third shell 15.

2

A high voltage arc sparkplug 41 extends through one side of the lower fitting 23 and into the fourth shell 37 directly below the atomizer bulb to ignite atomized fuel oil discharged from said bulb 35 in the upper portion of the fourth shell 37 whereby said shell 37 forms a primary combustion chamber 43 therein.

An annular horizontal central partition 45 in the outer shell divides the same into an upper preheating air chamber 47 and lower air and gas mixing chambers 49, and a horizontal partition 51 in the third shell 15 divides the same into an upper post combustion chamber 53 and a lower gas drying chamber 55.

An air supply line 57 from a suitable source of hot air under pressure extends into one side of the preheating air chamber 47 and a gooseneck hot air discharge pipe 54 extends from the top of said chamber 47 to the top of the upper section 21 of the turret 19 with its ends suitably connected to nipples 56, 58 threaded in the closure plate 5 and the top of the upper section 21, so that said pipe 54 discharges heated air downwardly through the turret 19 and through the space between the third and fourth shells 15, 37 into the post combustion chamber 51 to draw ignited gas out of the primary combustion chamber 43 through side openings 59 in the open lower end of said shell 37, and out of the lower end of said primary combustion chamber 43.

A baffle cup 61 is supported in the primary combustion chamber 43 directly below the sparkplug 41 on a rod 63 rising from the partition 51 and is of conical shape internally to bounce ignited gas back into the ignition area around the sparkplug terminals 65. An air inlet port 67 in the top of the fourth shell 37 provides for admitting air from the turret 19 past one side of the bulb 35 into said ignition area for combustion purposes.

A plurality of vertical choke tubes 69 having upper and lower ends thereof suitably fixed in the partition 51 and the bottom 13 of the second shell 11 extend through the drying chamber 15 and through which the ignited gas passed downwardly from the post combustion chamber 53 into a baffle cup 71 in the air and gas mixing chamber 49 surrounding the lower end of the second shell 11 and spaced from the shells 1, 11 and the partition 45 and having an axial open-ended updraft flue 73 extending upwardly into the drying chamber 55 and fixed in the bottom 13 of the second shell 11 in the axis of the latter to suspend said cup 71 in the air and gas mixing chamber 49 and communicating the air and gas mixing chamber with the drying chamber 55.

A circular series of discharge ports 75 in the lower end of the third shell 15 communicate with the bottom of the drying chamber 55 with the bottom of the gas discharge chamber 16.

A gas discharge pipe 77 extends laterally from the upper portion of the gas discharge chamber 16 out of the outer shell 1 for piping the fuel gas to burners or the like.

Referring now to the operation in detail, the oil supply line 33 is adapted to be connected to a suitable pump, not shown, to discharge fuel oil from a suitable source into the atomizer bulb 35 under high pressure to finely atomize the oil. The finely atomized oil is ignited at the ignition area around the terminals 65 of the sparkplug 41, thereby completely cracking the oil and the oil vapor formed which is forced to bounce back out of the cup 61 into the ignition area so that it is completely cracked in the primary combustion chamber 43. Hot air from the preheating air chamber issues under pressure from the hot air discharge pipe 54 into the turret 19 to pass down through the space between the shell 37 and the section 23 and third shell 15 to draw the burning vapor downwardly through the apertures 59 and the lower end of said shell 37 out of the primary combustion chamber 43.

into the post combustion chamber 53 to mix with the hot air and is prevented from ascending in said chamber 53 by the downdraft of the hot air in the post combustion chamber 53, thereby obviating flarebacks and explosions. From the post combustion chamber 53, the burning vapor or gas is forced under pressure in said chamber 53 down through the choke tubes 69 which retard its passage therethrough so that low grade waxes and tars are burned out of the vapor or gas to purify the same.

The purified vapor or gas discharges from the choke tubes 69 downwardly into the baffle cup 71 where it is agitated and issues from said cup 71 into the air and gas mixing chamber 49 for final mixing to issue through the updraft flue 73 into the drying chamber 55 from which it escapes through the apertures 75 into the gas discharge chamber 16 from which it discharges through the pipe 77.

As will be seen, the burning vapor in the post combustion chamber 53 highly heats the drying chamber and choke tubes 69 to bring about slow burning of waxes and tars out of the vapor of gas and the drying chambers 55 also prevent flarebacks into the post combustion chamber 53.

The heat from the preheating air chamber 47 may be used initially to preheat the primary combustion chamber 43 and hence the atomized oil so that the atomized oil can be ignited for gasifying.

The foregoing will, it is believed, suffice to impart a clear understanding of my invention without further explanation.

Manifestly, the invention is susceptible of modification and right is herein reserved to such modifications as fall within the scope of the appended claims.

What is claimed as new is as follows:

1. A liquid fuel oil gasifier comprising an upright cylindrical outer shell closed at its bottom, and having an annular top closure plate, an open bottom turret rising from said plate, a tubular primary combustion chamber depending out of said turret through said plate and having a lower apertured end, and a substantially closed upper end, a downwardly discharging atomizer in the upper end of said chamber, a pressure oil supply line extending into said turret and combustion chamber to said atomizer, a high voltage arc sparkplug in said turret with terminals directly beneath said atomizer to ignite atomized oil from said atomizer and gasify the same, a cylindrical post combustion chamber depending from said plate around said primary chamber, said turret and post combustion cham-

ber forming an annular downtake passage around said primary chamber, means for discharging a downdraft of hot air through said turret and passage to evacuate by suction the gas from the primary combustion chamber into the post combustion chamber, a lower air and gas mixing chamber in said outer shell, means communicating said post combustion chamber with said air and gas mixing chamber, a gas discharge chamber surrounding said post combustion chamber and having an outlet, and means communicating said air and gas mixing chamber with said gas discharge chamber.

2. A gasifier according to claim 1, and an internally conical baffle cup in said primary combustion chamber beneath and closely adjacent said terminals for bouncing the gas back toward said terminals.

3. A gasifier according to claim 1, said first-named means comprising an annular upper air chamber in said outer shell surrounding said gas-discharge chamber and adapted to contain hot air under pressure, and a hot air discharge pipe communicating said annular air chamber with said turret.

4. A gasifier according to claim 1, said second-named means comprising a plurality of vertical choke tubes depending from the bottom of said post combustion chamber and through which the gas passes from the post combustion chamber with a retardant flow for burning impurities out of the gas.

5. A gasifier according to claim 4, and a baffle cup in said air and gas mixing chamber into which said tubes discharge for agitating the gas.

6. A gasifier according to claim 4, said last-named means comprising a gas drying chamber depending from the post combustion chamber within and communicating at its bottom with said gas discharge chamber and through which said tubes extend in communication with the lower air and gas mixing chamber.
